MANUFACTURE OF BRUSHES

George N. Jacob, Jr., Belleville, and Ernest B. Wright, Jr., Montclair, N. J.

Application December 18, 1941, Serial No. 423,434

7 Claims. (Cl. 15—193)

This invention relates to the manufacture of brushes, particularly paint brushes of the type that comprise a back or frame having a recess or socket in which is a plastic or setting composition, such as vulcanized rubber, wherein the root or butt ends of the bristles are embedded. Brushes of this general character are shown in Patents No. 1,230,518 and No. 2,080,821, the backs or frames being formed of one piece of metal, generally aluminum, drawn or cast, and such backs or frames are preferred because they are strong, rigid and can be easily manufactured.

However, at the present time, due to scarcity of aluminum and certain other metals for civilian use, it has been necessary to provide other structures that can be made of other available metals, and without substantial increase in cost of production.

Bristles also are scarce and costly, and accordingly it is desirable to construct a brush so that the cost of the bristles shall be as low as possible consistent with a brush of good quality.

Therefore one object of our invention is to provide a brush of the character described the back or frame of which can be made of sheet metal, which shall be rigid, strong and durable, and which shall be relatively inexpensive.

Another object is to provide such a brush wherein the back or frame shall comprise a ferrule made of a strip of metal shaped into annular form, and novel and improved means for forming a socket in said ferrule to receive and firmly hold the plastic composition.

A further object is to provide in a brush back or frame, a novel and improved construction and combination of a ferrule and a plate extending transversely thereof intermediate the length of the ferrule so that said plate shall cooperate with the ferrule to form a socket for the plastic composition and to reinforce the walls of the ferrule so as to provide a rigid and strong construction.

Other objects are to provide a combination of such a brush back or frame and a spacer for bristles embodying novel and improved features of construction whereby the plastic composition, spacer and bristles shall be firmly held in said socket with a minimum portion of the bristles embedded in the plastic composition, whereby the cost of bristles shall be as low as possible.

Other objects, advantages and results of the invention will appear from the following description and the accompanying drawings in which

Figure 1 is a vertical longitudinal sectional view through a brush constructed in accordance with the invention.

Figure 2 is a transverse sectional view taken on the line 2—2 of Figure 1 with portions of the handle broken away.

Figure 3 is a detached plan view of the brush back or frame.

Figure 4 is a perspective view of the bottom plate for the socket of the brush back or frame.

Figure 5 is a perspective view of the spacer. Figure 6 is a view similar to Figure 2 showing 10 a modification of the invention.

Figure 7 is a top plan view of the bottom plate for the socket of the brush frame shown in Figure 6.

Figure 8 is a view similar to Figure 2 showing 15 another modification of the invention, and

Figure 9 is a detached perspective view of the bottom plate for the brush back or frame shown in Figure 8.

Specifically describing the embodiment of the 20 invention shown in Figures 1 to 4 inclusive, the brush back or frame comprises a ferrule A that is made of a strip of sheet metal shaped into an annular or tubular form with its ends riveted or otherwise secured together at 1. The shape and 25 dimensions of the ferrule may be modified as desired.

A plate 2 is arranged in the ferrule A intermediate the ends of the latter and rigidly secured to the walls of the ferrule so as to form 30 a socket opening through one end of the ferrule. The bottom and side walls of the socket are formed respectively by the plate 2 and the walls of the ferrule. As shown, the plate 2 has flanges 3 that are disposed in abutting relation to the 35 walls of the ferrule and are rigidly secured to said walls as by rivets 4.

The plate has portions offset from the general plane of the plate, which in the present instance consist of ears 5 stamped up from the plate to 40 form openings 6 and having portions 7 disposed in spaced and opposed relation to the general plane of the plate.

In assembling the bristles B in the frame or back A of the brush, a strip of paper or the like 8 45 is secured to the plate 2 at the side thereof opposite the ears 5 so as to close the openings 6. Plastic material 9, for example, rubber, is poured into the socket in semi-fluid condition. The bristles B are grouped together in a suitable frame, for example as shown in Patent No. 2,080,821, and the butt ends are pressed into the socket and into the plastic material 9 therein. The plastic composition is then allowed to set or harden, and where the composition is rubber, it 55 is vulcanized in the usual manner. If desired

the butt ends of the bristles may be dipped in fluid plastic composition before they are pressed into the socket, but this is not necessary.

Preferably a spacer C is utilized for dividing the bristles into layers. This spacer may consist of a piece of sheet metal stamped and bent into U-shaped cross section or channel form. This spacer initially may be arranged within the bristles while the latter are held in the frame as above described, and then pressed with the bristles into the plastic composition 8 in the socket. If desired, the side flanges 11 of the spacer may have openings 12 through which the plastic composition may flow to provide a bond between the spacer and the plastic composition.

Preferably the spacer also has tangs 13 at its ends that are inserted through certain of the openings 6 and the paper 8 and then clinched as at 14 upon the plate at the side thereof opposite the socket so as to firmly attach the spacer to the plate.

With this construction, it will be seen that the ears 5 will be embedded in the plastic composition so that the mass of plastic material will be firmly bonded to the plate 2 and positively secured in the socket of the brush back. The plate 2 will reenforce the ferrule so as to rigidify it and restrain bending or flexing of the walls of the ferrule during use of the brush, and the bristles will be firmly held in the mass of plastic material. At the same time, the spacer will be securely bonded with the mass of plastic material and firmly attached to the plate 2 by the clinched tangs 13. If desired, the walls of the ferrule may be formed with grooves or ribs as indicated at 15 to provide further bonding of the plastic material with the walls of the socket.

The structure is simple and relatively inexpensive, and due to the firm mounting of the bristles in the brush back, it is unnecessary to insert the bristles as far into the socket as has been required in prior art structures, so that the cost of the bristles may be the minimum consistent with a brush of good quality.

The ferrule may be attached to a handle D in the usual manner as by inserting the handle into the end of the ferrule and connecting the parts by nails or other fastener members 16. The edges of the flanges 3 may conveniently serve as stops to be abutted by the end of the handle as the latter is inserted into the ferrule, thereby to facilitate location of the handle in the ferrule.

In the modification of the invention shown in Figures 6 and 7, the bottom plate 17 of the socket is of the same general structure as the plate 2, the main difference being that the plate 17 has an undercut or dove-tailed groove 18 instead of the ears 5 for providing an interlock or bond between the plate and the mass of plastic material. The spacer E may be in general similar to the spacer C, and the spacer E may or may not have tangs and the plate 17 may or may not have openings for the tangs, as desired.

In Figures 8 and 9 the bottom plate 19 of the socket, which corresponds to the plate 2, is shown as provided with tongues 20 at its edges to be inserted through slots 21 in the walls of the ferrule for connecting the plate to the ferrule. The tongues 20 may be upset or clinched against the outer sides of the ferrule walls as shown in Figure 8, and if desired the tongues may be soldered to the ferrule walls.

It will also be understood that the bottom plate may be rigidly connected to the ferrule in any other suitable manner to form a socket in

the ferrule and to reenforce the walls of the ferrule.

Other modifications in the details of structure of the brush will occur to those skilled in the art as within the scope of the invention.

Having thus described our invention, what we claim is:

1. In a brush, a tubular sheet metal ferrule, a separate sheet metal plate within and disposed transversely of the ferrule intermediate the length of the latter with its edges abutting the walls of the ferrule and formed with integral projections, means including said projections rigidly securing said plate to said walls to form a socket opening through one end of the ferrule, said plate constituting the bottom wall of said socket, a mass of plastic material in said socket, bristles having their ends embedded in said plastic material, said plate having integral portions offset from the general plane thereof extending inwardly of the socket and interlocking with said mass of plastic material, and a handle secured in the other end of said ferrule.

2. In a brush, an annular ferrule, a plate extending transversely of the ferrule intermediate the length of the latter to form a socket opening through one end of the ferrule, said plate constituting the bottom wall of said socket and having flanges at its edges flatwise abutting and rigidly secured to the walls of the ferrule, a mass of plastic material in said socket, and bristles having their ends embedded in said plastic material, said plate having portions interlocking with said mass of plastic material.

3. In a brush, an annular ferrule, a plate extending transversely of said ferrule intermediate the ends of the latter and forming a socket opening through one end of the ferrule, said plate constituting the bottom wall of said socket, means rigidly securing said plate to the walls of the ferrule, a mass of plastic material in said socket, bristles having their ends embedded in said plastic material, and a spacer set in said plastic material and dividing the bristles into rows, there being a direct interlocking connection between said spacer and said plate for securing the spacer to the plate.

4. In a brush, a ferrule, a plate extending transversely of said ferrule intermediate the ends of the latter and forming a socket opening through one end of the ferrule, means rigidly securing said plate to the walls of the ferrule, a mass of plastic material in said socket, bristles having their ends embedded in said plastic material, a spacer set in said plastic material and dividing the bristles into rows, said plate having openings and said spacer having tangs passing through said openings and clinched upon said plate.

5. In a brush, a ferrule, a plate extending transversely of said ferrule intermediate the ends of the latter and forming a socket opening through one end of the ferrule, means rigidly securing said plate to the walls of the ferrule, a mass of plastic material in said socket, bristles having their ends embedded in said plastic material, a spacer set in said plastic material and dividing the bristles into rows, said plate having ears struck up therefrom and forming openings in the plate, said ears projecting into the socket with portions in spaced opposed relation to the general plane of said plate and embedded in said plastic material, and said spacer having tangs passing through certain of said openings and clinched upon said plate.

6. In a brush, a ferrule, a plate extending trans-

versely of said ferrule intermediate the ends of the latter and forming a socket opening through one end of the ferrule, the walls of the ferrule having slots and the edges of said plate having tongues projecting through said slots and upset against the ferrule walls to rigidly secure the plate to the ferrule, a mass of plastic material in said socket, and bristles having their ends embedded in said plastic material, said plate having portions interlocking with said mass of plastic material.

10

7. In a brush, a ferrule, a plate extending transversely of said ferrule intermediate the ends of the latter and forming a socket opening through one end of the ferrule, said plate having an undercut groove opening into said socket, a mass of plastic material in said socket and having a portion in said groove to interlock said mass with said plate, and bristles having their ends embedded in said mass of plastic material.
